UNITED STATES PATENT OFFICE.

JAMES P. ADAMSON, OF ST. PAUL, MINNESOTA.

WALL-RADIATOR BRACKET.

1,158,151.

Specification of Letters Patent. Patented Oct. 26, 1915.

Application filed February 9, 1915. Serial No. 7,164.

To all whom it may concern:

Be it known that I, JAMES P. ADAMSON, citizen of the United States, resident of St. Paul, county of Ramsey, State of Minnesota, have invented certain new and useful Improvements in Wall-Radiator Brackets, of which the following is a specification.

The object of my invention is to provide a support for a wall radiator which will allow the convenient vertical adjustment thereof to the desired location on the wall and the proper distance from the floor line.

A further object is to provide a bracket having improved means for securing it to the wall and to the radiator.

The invention consists generally in various constructions and combinations, all as hereinafter described and particularly pointed out in the claims.

In the accompanying drawings forming part of this specification, Figure 1 is a front elevation of a wall radiator, embodying my invention, Fig. 2 is a vertical sectional view of the same, Fig. 3 is a front view of a wall bracket, Fig. 4 is a sectional view on the line $x-x$ of Fig. 3, Fig. 5 is a sectional view on the line $y-y$ of Fig. 2.

In the drawing, 2 represents a wall of the room on which the radiator is mounted, and 3 a wall radiator of ordinary construction.

4 is a bracket, made of suitable material and having a flat rear face 5 to bear on the wall 2 above the base board 6. At the lower end of the bracket, near the top of the base board, an outwardly projecting bend 7 is formed, terminating in a stirrup 8 in which the lower end of the radiator is seated at a suitable distance above the floor line. At the top of the bracket is an outwardly and upwardly turned arm 9 having a transverse slot 10 therein to receive a bolt 11 having a washer and lock nut at its inner end and a tapered nut 12 at its outer end that is seated against the wall of the adjacent radiator sections. This bolt is capable of lateral adjustment in the slot in the bracket to adapt it to its seat on the sections of the radiator. At the upper and lower portions of the middle section of the bracket I provide longitudinal slots 13 having outer flat, roughened or corrugated surfaces 14 to engage the corresponding surfaces of washers 15 which are mounted on lag screws or bolts 16 inserted into the slots 13 and into the wall in the rear of the bracket. By loosening these lag screws or bolts, the bracket can be adjusted

vertically to adapt it for the desired elevation of the radiator and when once the bolts are tightened there will be no danger of slipping out of place. As indicated in Fig. 1, the heads of the bolts are accessible between the sections of the radiator for tightening or loosening them, as occasion may require.

In using my invention, the brackets for a series of radiators on one line may be secured to the wall and the radiators mounted thereon and then, by loosening the bolts or lag screws slightly, the brackets can be raised or lowered to obtain the requisite difference in elevation for drainage purposes. As soon as the radiators are adjusted at the desired distance from the floor line, the bolts are tightened and the brackets held firmly in position on the wall.

The brackets may be made in different sizes, according to the style and size of the radiator used, and in various ways the details of construction may be modified and still be within the scope of my invention.

I claim as my invention:

1. The combination, with a wall radiator, of a bracket having a middle portion provided with a surface adapted to be seated against the wall of the room on which the radiator is suspended, the lower end of said bracket having a stirrup in which the radiator is seated, the upper end of the bracket having means for securing it to the radiator sections, said middle portion having vertical slots therein and said bracket having roughened surfaces around said slots and bolts and having washers provided with roughened surfaces to engage the corresponding surfaces around said slots, said bolts, when loosened, allowing vertical adjustment of the bracket thereon.

2. A wall radiator bracket having a middle portion adapted to be seated against the wall above the base board and provided with a stirrup at its lower end in which the lower end of the radiator is seated, and an outwardly projecting upper end having means for securing it to the top of the radiator, said middle portion having longitudinal slots therein and bolts fitting within said slots for securing said bracket to said wall, said bolts, when loosened, allowing vertical adjustment of said bracket to raise or lower the radiator to vary its distance from the floor line, for the purpose specified.

3. A wall radiator bracket having a mid-

dle portion adapted to be seated against the wall above the base board and provided with a stirrup at its lower end in which the lower end of the radiator is seated, said bracket having means for securing the upper portion of the radiator thereto, said middle portion having longitudinal slots therein and bolts fitting within said slots for securing said bracket to the wall, said bolts, when 10 loosened, allowing vertical adjustment of

said bracket to raise or lower the radiator to increase or decrease the distance from the floor line, for the purpose specified.

In witness whereof, I have hereunto set my hand this 28th day of January, 1915. 15

JAMES P. ADAMSON.
